UNITED STATES PATENT OFFICE.

EINAR GUSTAF EVALD HOGNER, OF STOCKHOLM, SWEDEN.

MECHANICAL PENCIL.

Application filed November 18, 1925, Serial No. 69,872, and in Sweden November 19, 1924.

The present invention relates to lead pencils provided with a feeding device for the leads. The most advantageous application of the invention is to such pencils as are provided with a magazine for the leads. Said magazine may be constructed in such a way that the leads may be consecutively propelled to a central place in the magazine to allow them to be engaged by the feeding device, and propelled by said device to the place where they are to be consumed, viz, at the point of the pencil. The feeding device may be adjustable in such a way as to impart a forced movement to the parts of said device which have to feed the leads, said forced movement effecting the feeding operation. When a lead has been sufficiently advanced, at least so much as to allow it to leave the magazine, a device, already well known, will operate to release said parts of the mechanism from the imposed movement so as to allow the feeding device to be pulled or pushed and a fresh lead from the magazine to be advanced in front of the feeding device.

The present invention contemplates a device which on pulling or pushing the feeding device restores this device to perform the forced movement which advances the fresh lead.

The accompanying drawing shows an embodiment of the invention, and in this drawing:

Figure 1 is a view of an inner sleeve which contains the feeding device.

Fig. 2 is a longitudinal section of the complete pencil with parts in elevation.

Fig. 3 is a fragmentary sectional view of the pencil, illustrating the operation of the quick release mechanism.

Fig. 4 is a fragmentary sectional view showing the feeding device at the end of its feeding movement.

Fig. 5 is a perspective view of the sleeve and the feeding device of Fig. 1.

Figs. 6 and 7 are cross sectional views on the lines 6-6 and 7-7 of Fig. 2.

The pencil is provided with a sleeve B, threaded along a certain part of its length and arranged to rotate within a sleeve forming the shell of the pencil. By rotating the sleeves relatively to each other leads contained in the magazine will be advanced to the axis of the pencil and from this place they may be guided by a channel to the point of the pencil.

A feeding pin or lead pusher G is rigidly

attached to a crosshead H which is at one side provided with teeth adapted to engage the threads of the sleeve B and protrudes through a longitudinal notch J arranged in the wall of a sleeve I adapted to be inserted in the sleeve B, the lead pusher being thus adapted to reciprocate in sleeve I. The other side of the crosshead is provided with a cam r and runs in a groove-shaped part K, which is arranged to slide, within certain limits, in the sleeve I. At the end of sleeve I adjacent to the point of the pencil said grooved part K may, when the sleeves B and I are axially separated, protrude, to some extent, through said sleeve I, as at P. A novel feature of the invention as to this embodiment is a stop d located in a special member C attached, for instance by means of threads, to the sleeve B; a projection s located on the part K protrudes through a longitudinal aperture t from the sleeve I. The projection s may be split and the groove K, in order to be more elastic, may be slotted at its bottom, while if desired, the projection may be broadened to overhang the edges of the aperture t.

A novel feature of the invention is the fact that the sleeve I has, at one end, a larger diameter than along the greater portion of its length. Said enlarged portion W fits the internal diameter of the threading of the sleeve B. The smaller diameter of the sleeve I, above the enlargement, fits the circular hole formed by the edge d. In this way the projection s runs clear of the wall of the sleeve B.

The arrangement operates as follows:

The sleeve I, with the channel member K, cross head H and pusher G assembled therein, is inserted in the sleeve B, which may be effected after removal of the member C from the sleeve B and after taking off a button or handle threaded on the sleeve I, whereupon the member C is slid over the sleeve I and threaded to the sleeve B, the button then being replaced on the sleeve I. The assembling of sleeves B and I causes the channel member K to be retracted, from the projected position of Figs. 3 and 5 to the position of Fig. 2, due to the end of said channel member striking the tapered bottom of sleeve B. By relative rotation of the sleeves, the cross head H is propelled by the threads of the sleeve B, and in this manner the feeding pin G pushes a lead from the magazine and forces it through the point of the pencil. As the lead is consumed and the

cross head H approaches the lower end of the sleeve B, the cam r on the cross head snaps into a notch q, in the bottom of the groove K (Fig. 4). Then the sleeve I is 5 pulled back, the teeth of the cross head H being clear of the threads of the sleeve B. As the parts approach the position of Fig. 3, the projection s strikes against the stop d by which the projection s and consequently 10 the groove K are displaced in the sleeve I in the direction toward the point of the pencil. By this operation the cam r is forced out of the notch q and the crosshead, now located in an unthreaded and sufficiently large 15 portion of the sleeve B, will occupy such a position as to allow it only by screwing to be brought through the threaded portion of the sleeve B. By rotating the sleeve B in the outer sleeve or shell—rotating the magazine 20 automatically for instance by a spring arrangement—a fresh lead is brought from the magazine in front of the feeding pin G. On again screwing the crosshead H forward the fresh lead is brought toward the point 25 of the pencil.

Further embodiments of the invention may be suggested. For the stop d a stop constructed in any other way may be substituted, it may be placed in different positions in the 30 sleeve B and may be mounted in the other ways, for instance, directly in the sleeve B without the aid of any special member. The portion of the sleeve I, which is given a large diameter, may be placed at any other 35 place than at the end of the sleeve. The projection s may have different constructions according to the construction given to the member K. This member need not have the shape of a groove. Such variations should 40 be considered as different embodiments of the present invention.

Claims:

1. A mechanical pencil comprising a longitudinal, internally threaded sleeve, and a 45 lead-feeding mechanism slidable and rotatable therein and including a lead-pusher and a toothed element adapted to engage the threads of said sleeve and having a cam opposite its teeth, said mechanism also including a slidably mounted grooved member 50 engaging said cam to press the teeth into engagement with said threads and having a notch to receive the cam in order to allow the toothed element to be disengaged from said threads, and a projection extending transversely through and beyond the wall of the 55 feeding mechanism, said sleeve having a stop adapted to be engaged by said projection, so that, when the toothed element is disengaged 60 from the threads and its cam projects into the notch of the grooved member, relative sliding of the sleeve and the feeding mechanism brings the projection into engagement with the stop and slides the grooved member 65 with respect to the feeding mechanism,

whereby the cam is forced out of the notch and the toothed element is projected into the path of the threads.

2. A mechanical pencil as claimed in claim 1, in which the wall of the feeding mechanism above and below the projection on the grooved member is spaced inwardly away from the threads of the sleeve, and the stop on the sleeve comprises a removable collar having an inwardly extending flange against which said wall is slidably and rotatably supported.

3. In a mechanical pencil of the kind in which the feeding of a lead is accomplished by means of a pusher movable by means of a propelling device said pencil comprising a control-member, adapted in the feeding of the lead, to maintain cooperative engagement between said pusher and said device, and means for releasing the engagement between said pusher and said device; the arrangement of means comprising a projection on the said control-member, and a stop in relation to which said projection is movable, disposed in the pencil in the path of said projection for actuating said control-member for the purpose of reinstating said engagement.

4. In a mechanical pencil of the kind in which the feeding of a lead is accomplished by means of a pusher movable by means of a propelling device, said pencil comprising a control-member movable in a casing, said control-member being adapted, in the feeding of the lead, to maintain cooperative engagement between said pusher and said device, said casing being movable in the pencil, and means for releasing the engagement between said pusher and said device at the foremost position of the pusher, adjacent to the point of the pencil, so that the pusher can be freely moved backwards; the arrangement of means comprising a projection on said control-member extending through a slot formed in the wall of said casing and a stop disposed in the pencil in the path of the said projection and adapted to be engaged by said projection when the casing and the pusher are moved to their hind-most position.

5. In a mechanical pencil comprising a lead-feeding mechanism normally in engagement with a propelling device, said pencil comprising a control-member slidably mounted in the lead-feeding mechanism and adapted, in the feeding of the lead to maintain cooperative engagement between said feeding mechanism and said propelling device, and means for releasing the engagement between said propelling device and said feeding mechanism, the arrangement of means for imparting to said control-member a sliding motion, for the purpose of reinstating said engagement.

6. A mechanical pencil comprising a lon-

itudinal internally threaded sleeve, a lead-
feeding mechanism slidable and rotatable
therein and including a lead-pusher and a
toothed element adapted to engage the
5 threads of said sleeve and having a cam op-
posite its teeth, said mechanism including a
slidably mounted control-member adapted,
in the feeding of the lead, to maintain co-
operative engagement between said toothed
10 element and said threaded sleeve, said con-
trol-member having a notch to receive the
cam to allow the toothed element to be dis-
engaged from said threads, and a projection
on said control member extending transverse-
15 ly beyond the feeding mechanism, said sleeve
having a stop adapted to be engaged by said
projection, so that, when the toothed element
is disengaged from the threads and its cam
projects into the notch the control-member,

relative sliding of the sleeve and the feed- 20
ing mechanism brings the projection into
engagement with the stop and slides the con-
trol-member with respect to the feeding
mechanism whereby the cam is forced out
25 of the notch and the toothed element is pro-
jected into the path of the threads.

7. A mechanical pencil as claimed in claim
6, in which the wall of the feeding mecha- 30
nism above and below the projection on the
control-member is spaced inwardly away
from the threads of the sleeve, and the stop
on the sleeve comprises a removable collar
having an inwardly extending flange against
35 which said wall is slidably and rotatably sup-
ported.

In testimony whereof I affix my signature.

EINAR GUSTAF EVALD HOGNER.
